UNITED STATES PATENT OFFICE

170,905

SHEARS

Leonard Blanchaert, Milan, Italy, assignor to
Coltellerie Riunite di Caslino E. Maniago, a
limited corporation of Italy

Application August 22, 1952, Serial No. 21,165

Term of patent 7 years

(Cl. D22—5)

To all whom it may concern:

Be it known that I, Leonard Blanchaert, a citizen of Belgium, residing at Milano, Italy, have invented a new, original, and ornamental Design for a Shears, of which the following is a specification, reference being had to the accompanying drawings, forming a part hereof.

Fig. 1 is a plan view showing one side of a shears in a closed position embodying my new design.

Fig. 2 is a plan view of the side opposite that shown in Fig. 1 with the shears open.

Fig. 3 is an edge view thereof from one side.

Fig. 4 is an edge view thereof from the opposite side.

I claim:

The ornamental design for a shears, as shown.

LEONARD BLANCHAERT.
